UNITED STATES PATENT OFFICE.

THOMAS M. TOPP, OF SAN FRANCISCO, CALIFORNIA.

ORE-FEEDER.

No. 910,097.

Specification of Letters Patent.

Patented Jan. 19, 1909.

Application filed November 5, 1907. Serial No. 400,738.

To all whom it may concern:

Be it known that I, THOMAS M. TOPP, a citizen of the United States, residing at the city and county of San Francisco and State of California, have invented new and useful Improvements in Ore-Feeders, of which the following is a specification.

My invention relates to a device for feeding material intermittently in small quantities. It is especially designed for feeding ore from a receptacle or container, and delivering it to a crushing mill of suitable character.

It consists in the combination of parts, and in details of construction which will be more fully explained by reference to the accompanying drawings, in which—

Figure 1 is a side elevation showing my ore feeder attached to a crushing mill. Fig. 2 is a section on line X—X of Fig. 1.

It is the object of my invention to provide a device for feeding ore to crushing mechanisms, and a means by which the feed is regulated to the requirements of the mill.

This device may be applied to any form of crushing mill. In Fig. 1, I have shown it as applied to that class of crushing mills in which a quadrant-shaped crusher is caused to oscillate or rock back and forth upon the surface between which and the crusher the ore is to be crushed.

A is a hopper or container of any description in which the ore is placed ready for feeding.

The feeder consists of a flat conical disk or surface 2 which preferably has projections upon its surface, as shown at 3. This disk is mounted upon a vertical stud 4, and is located beneath the opening at the bottom of the ore container.

The container in the present case is shown as being convergent downward, or hopper-shaped, and the mouth or opening is of sufficient proportionate size to allow the ore to pass down and rest upon the disk 2. This disk and its stud are so mounted that they may be raised or depressed. In the present case the stud 4 has its lower end screw-threaded, and may have a rectangular end, as at 4^a for the reception of a wrench by which the stud may be turned through the nut 6 so as to raise or depress the disk, dependent upon the fineness or coarseness of the ore to be fed, and the rapidity with which feed is required.

7 is an arm which is attached to the hub of the disk 2, this hub being bored to fit and turn on the upped end of the stud 4. This arm 7 extends outwardly to one side and has a vertically slotted portion 7^a, through the slot of which a rod 8 passes, and across the frame-work 9 which supports the container A. This slot being slideable upon the rod, will allow the cone 2 and the arm 7 to be moved up and down in unison with the movement of the screw 4 to regulate the feed. I have here shown a portion of the transverse frame 10 upturned and bent over to form a hook as shown at 10^a, and this hook may be engaged with the side of the mortar in which the crushing takes place. The outer side of the feeder is here shown as provided with a leg 12 which may rest upon the floor by the side of the mortar, thus furnishing a convenient support, and retaining the feeder in close connection with the crushing mortar.

The disk 2 is caused to oscillate from side to side, and as the ore rests upon the surface of the disk, it will be seen that the constant oscillating movement will agitate the ore and cause it to gradually work off the edges of the disk, and thus fall into a chute 13 which is arranged beneath the disk, with the lower end discharging into the mortar and beneath the crushing shoes of the apparatus. In order to produce this oscillating motion, I have shown suitably stiff springs 17, which are located upon the rod 8 and on each side of the slotted arm 7, their outer ends abutting against a portion of the framework as at 18. The end of the arm 7 extends sufficiently beyond the rod 8, or an equivalent extension is formed as at 14, and this is in line with a moving part of the crusher so that the latter will contact with it at each reciprocation or movement of the crusher. In the present case I have shown an arm 20 extending downward from the pin or shaft which oscillates the rocking crusher, and this arm engages the end of the arm 14 as it passes, thus pulling the arm 14 to one side until in its arc of movement it passes out of range of the arm 20, when the springs will act to return the arm 14, and with it the disk 2 to its normal position. When the oscillating crusher returns in the opposite direction, the same engagement will act to rotate the disk in the opposite direction until the end 14 is again released, when the spring 110

17 will again return it to its normal position. Thus the oscillations of the crusher continually oscillate the disk with an abrupt motion which acts to gradually shake the ore down 5 and off the edge of the disk and into the crushing mortar. As the ore in the mortar increases, it will be obvious that the crusher will also be raised and the length of the arm 20 is so regulated that when a sufficient 10 amount of ore for best results has been fed into the mortar, this arm will cease to engage with the arm 14, and the feed will be temporarily stopped until the ore already within the mortar has been sufficiently 15 crushed to allow the crushing device to again be lowered until the actuating arms engage when the feed will recommence. The feed is thus rendered automatic and the amount fed is regulated by the stud 4, 20 as previously described.

If this apparatus is designed to be used upon a rising and falling stamp mill, it will only be necessary to fix a wedge-shaped inclined part to the stamp stem, or some 25 rising and falling portion of the mill, and locate the arm 14 in such position that the wedge will engage upon one side of the arm and thus oscillate the feeder. In this case the shape of the wedge will insure the cessation 30 of the feed when the amount of ore below the stamp becomes sufficient to prevent its falling far enough to engage the arm. It will be manifest that in a similar manner this feed may be adjusted to any character 35 of crushing mill.

It will be observed that the slot in the enlarged portion 7^a is so much larger than the rod 8 that the arm 7 can oscillate without binding on same.

40 Having thus described my invention, what I claim as new and desire to secure by Letters Patent is—

1. An ore feeder consisting of a horizontally disposed conical disk, a vertical stud 45 therefor, an ore container having an open mouth beneath which the disk is placed, and means whereby the disk is oscillated in a horizontal plane, said means including an arm horizontally-disposed having one end attached to the disk and having its other or 50 outer end arranged in the range of action of a contacting part of the crusher, and resilient connections operating against each side of the arm.

55 2. In an ore feeder and in combination with an open bottomed ore container, a disk having a conical upper surface with protuberances thereon, a vertical stud upon which the disk is mounted in line beneath the container mouth, and means by which the disk is oscillated in unison with the operation of the crusher, said last named means comprising a horizontally-disposed arm having its inner end connected to said stud and having its 60 outer end arranged in the field of reciprocal

action of a part carried by the crusher, whereby said arm may be moved in a horizontal plane substantially at right-angles to the axis of the stud, and springs upon each side of the arm acting in opposition to the 70 pressure exerted by the contacting part of the crusher.

3. In an ore feeding device, and in combination with an open - bottomed ore - container, a conical disk having protuberances 75 upon its upper surface, a vertical stud upon which the disk is mounted, means by which the disk and stud may be raised and depressed with relation to the container, and means by which an oscillating motion is con- 80 veyed to the disk, said last-named means comprising an arm having one portion attached to the disk and having another portion arranged in the field of reciprocal action of a part carried by the crusher, the intermediate part of the arm being spring-pressed whereby the arm will yield in lateral planes when engaged by the contacting part 85 of the crusher.

4. In an ore feeder of the character de- 90 scribed, an open-bottomed ore-container, a low conical disk having protuberances upon its upper surface, a vertical stud upon which the disk is mounted, an arm extending at right angles with the stud, said arm having 95 its inner end attached to the disk and having its outer portion provided with a vertical slot, and a fixed rod upon which said arm is slidable, screw-threads formed upon the lower end of the stud, a fixed nut through 100 which said threads are turnable whereby the disk may be raised or depressed with relation to the container, means for operating said arm, and a chute through which ore-discharged from its periphery is conducted to 105 a crushing mechanism.

5. In an apparatus of the character de- 110 scribed, an open-bottomed ore-container, a disk having protuberances upon its upper surface, a vertical stud upon which said disk 115 is carried, an arm projecting to one side from the disk, springs by which said arm and the disk are normally maintained in position, an arm projecting from a movable part of the crusher adapted to engage the 115 projecting end of the disk-connected arm to move said arm and disk until released from the actuating arm, the springs returning the disk and its arm to their normal position when released.

6. In an apparatus of the character de- 120 scribed, an open-bottomed ore-container, a horizontally turnable disk mounted below the mouth of the container, means for supporting and adjusting the disk up and down 125 with relation thereto, an arm carried by the disk, another arm carried by a movable portion of the crushing mill adapted to engage the disk arm and swing it from side to side, springs by which the disk arm is returned to 130

its normal position when released from the actuating arm, said actuating arm being so located as to be disengaged from the disk-carrying arm by the increase of ore in 5 the crusher, and to be again engaged therewith by the decrease of supply.

In testimony whereof I have hereunto set

my hand in presence of two subscribing witnesses.
